METAL MANUFACTURING APPARATUS

Clarence W. Hazelett, Greenwich, Conn.

Application June 2, 1949, Serial No. 97,675

13 Claims. (Cl. 22—57.4)

1

This invention relates to the production, directly from molten metal, of various metal shapes, and more particularly metal strip. The art has for many years sought ways and means for the manufacture of metal shapes, and particularly metal strip, directly from the molten metal, and I have personally contributed a number of processes that I have covered by patent. However, my present invention represents a considerable departure from earlier methods and apparatus.

In my present invention, I depart from my earlier contributions to the art through the utilization of chilling surfaces that are shaped relatively to one another in one particular zone so as to contain a bath of molten metal, the chilling surfaces moving into particular relationship beyond said bath of metal whereby to carry metal from the first zone and from the bath of metal into what I term a second zone. As a particular feature of my invention, the bath of metal is formed through the shaping of a chilling surface that is preferably in the form of a band, and while this band is preferably continuous, it may be merely a long strip.

As a preferred form of the invention, I utilize spaced chilling surfaces in the form of upper and lower flexible bands, the bands containing in one zone of their travel the bath of metal, and moving preferably into substantially closer and parallel relationship in a second zone of travel. While moving to this second zone of their travel, the bands carry with them metal that is chilled and solidified through contact with the bands, together with a quantity of molten metal moving between the chilled or solidified parts of the metal, depending on the spacing of the bands. In the second zone, means are provided for finally solidifying all of the metal and thereby producing the particular desired metallic shape, which in the preferred form of my invention is metal strip.

In the carrying out of my invention, I utilize a number of important structural features that are part of the invention I have already described generally, and which are in themselves quite important. Thus, as a particular feature of my invention, the travelling bands are maintained in a particular shape by the tensioning of the bands relatively to shaping means such as rollers. It is in this manner that the bath of metal is formed, as will presently appear quite clearly.

For a full understanding of this invention it is important to appreciate that a spout which can continuously carry substantial amounts of molten metal such as steel, must be lined with refractory material and must be several inches

2

in height. Because the great tonnages of strip commercially used are $\frac{1}{4}$ " thick or less, it is impossible therefore to use a spout to convey molten metal between cooling surfaces having a spacing even nearly approaching the thickness of the desired product. This is also true to a less but nevertheless real extent in the fabrication of brass, copper and aluminum.

It is also essential to have the incoming stream of metal from the spout enter a bath of metal rather than directly strike a cooling surface, in order to contribute a quality product. Without a bath of metal, the surface of the resulting product is spoiled by the irregular solidifying and splattering of the metal, as will be appreciated by those skilled in the art. Furthermore, a high velocity stream that strikes directly a cooling surface will scour and burn that surface and may even weld thereto, whereas a bath of metal will accept and cushion the flow of metal and thereby help produce uniform and smoothly surfaced products while avoiding damage to the cooling surfaces. As a feature of my invention, the cooling surfaces formed by the bands I prefer to use are spaced and shaped to provide a bath of metal and room for the necessary spout. At the same time, and as will be emphasized below, the thickness of the metal bath at its side edges is never greater than the thickness of the edges of the final strip turned out by my apparatus.

In apparatus previously developed by me, large quantities of metal strip have been fabricated, but a most serious limitation existed in the production of alloy strip. This difficulty resulted because the considerable pressures required by prior art processes and machinery to make solid strip caused excessive segregation of the alloy's constituents. Thus, it is well known that the constituents of alloys solidify at different temperatures. If no pressure is exerted on an alloy at the solidifying temperature of the high melting point constituents, the lower melting point constituents will maintain the alloy in a "hot-short" condition, and the strip will fall apart as it comes from the mill. On the other hand, if pressure is exerted at the particular point, it will squeeze out the unsolidified constituents, and these constituents will solidify in pockets to yield a non-uniform product.

As a feature of my invention, I obviate these difficulties by producing a strictly cast strip without external pressure. Thus, I provide a first zone in which my cooling surfaces or bands move, and are shaped and guided to provide a space therebetween for a spout and a substantial bath,

and in which zone the upper and lower surfaces of the final metal strip are solidified. There is also provided a second zone in which the cooling surfaces or bands are brought into that spaced relationship required by the final product and before the metal of the central section of the product has solidified. I extend this second zone for a predetermined distance to permit the final solidification of all the metal, including both the high and low melting point constituents present in the central portions of the strip, and before the strip emerges from the mill. This is all accomplished without pressure, thereby eliminating all segregation and producing simultaneously a solid strip.

A bath of molten metal must be sealed at the edges thereof to contain the metal therein. Many efforts have been made to contain by side dams the edges of a metal bath while not cooling a greater thickness of metal at the said edges than the thickness of the final product desired. However, so far as I am aware, none of these efforts have been successful. A greater thickness of metal than desired is thus solidified in prior art mills because the sides of the bath of metal are of considerable area and are in contact with dams of the same area that provide considerably larger chilling surfaces than the edges of the strip being formed. Naturally, the excess of metal thus solidified at the edges creates great difficulties. In this invention I have overcome these difficulties by the use of flexible cooling surfaces that are shaped to contain the bath of metal, provide room for a spout, and yet limit the thickness of the metal at the side edges of the bath to a thickness not greater than the thickness of the final product to be produced.

As a further specific feature of this part of my invention, the flexibility of the cooling surfaces permits them to be pressed together or against side dams that are no thicker than the final product, the dams preventing the escape of molten metal or the entry of cooling fluids. Moreover, as will appear presently, the side dams taper in the proper direction so as to allow free movement of the metal strip relatively to the machine.

As a still further feature of the invention, unique and novel means are utilized for cooling the bands, and for holding the bands in shape in the cooling zone. A large volume of water must be introduced against the bands at all points opposite the portions thereof in contact with hot metal. I have provided magnetic means tending to hold the bands against a particular backing surface or surfaces, thereby setting up spaces through which water may flow while holding the bands in particular relation to one another and to the backing surfaces.

As a further feature of the invention, I provide drying means that are moved automatically out of drying relation to the bands when the movement of the bands is stopped, and which means move into drying relation to the bands when the bands move to form the metal strip.

As a still further feature of the invention, I provide means for tilting the guide rollers of the bands, when necessary, in order to adjust the lateral positions of the bands, this being accomplished automatically as will appear presently.

As a further feature of the invention I use metal bands that are wider than the rollers over which they move and which therefore permits greater bowing of the bands without exceeding the elastic limits thereof, especially at the edges.

As further features of the invention, I pro-

vide a number of modified forms of side dams that I shall describe in particular detail in the specification.

Also, I provide, as a modification of my invention a substitute for the rollers for shaping the bands, using instead of rollers a stationary casting, and which I shall refer to later in the specification.

I shall also show and described diagrammatically a modification of my invention whereby there may be formed a solid ingot block through the continuous flow of molten metal.

I have thus outlined rather broadly the more important features of my invention in order that the detailed description thereof that follows may be better understood, and in order that my contribution to the art may be better appreciated. There are, of course, additional features of my invention that will be described hereinafter and which will form the subject of the claims appended hereto. Those skilled in the art will appreciate that the conception on which my disclosure is based may readily be utilized as a basis for the designing of other structures for carrying out the several purposes of my invention. It is important, therefore, that the claims to be granted me shall be of sufficient breadth to prevent the appropriation of my invention by those skilled in the art.

Referring now to the drawings, Fig. 1 is a vertical section through a machine in which my invention is embodied. Fig. 2 is a section taken along lines 2-2 of Fig. 1. Fig. 2a shows a section of a modified form of one of the backing surfaces toward which the bands are pressed. Fig. 3 is a section taken substantially along lines 3-3 of Fig. 1. Figs. 4 and 5 are sections taken respectively along lines 4-4 and 5-5 of Fig. 1. Fig. 6 is a perspective view showing the operation of a roller tilting means whereby the lateral position of one of the bands is determined. Figs. 7 and 8 are modifications of the water jacketing means shown in Fig. 5. Fig. 9 is a modification showing ribbons of metal used as side dams. Fig. 10 is a modification showing the utilization of a form such as a casting instead of rollers for shaping the metal bands. Fig. 11 shows a modified form of side dam. Fig. 12 shows diagrammatically mechanism used for the forming of ingots.

Referring now more particularly to the drawings, reference numeral 10 indicates an upper structural frame constituting part of my invention, while reference numeral 11 indicates a lower frame supported by legs 12 and 13. The upper and lower frames 10, 11 are connected at one end by a suitable standard 14 and at intermediate points by standards 15 and 16. It will be well to indicate here that the manner in which the means of my invention are fabricated is not particularly important, and per se is not the invention here to be claimed.

The upper chilling band of my invention is designated by reference numeral 17, while the lower chilling band is indicated by reference numeral 18. At the extreme left end of the machine of Fig. 1, the band 17 passes over a roller 19 rotating on a shaft 19a carried by opposed bearing arms 20 suitably secured for integral movement with a piston rod 21 movable in a hydraulic ram cylinder 22. Ram cylinder 22 is fixed to a strut 23 extending between the upper and lower structural members of the frame 10 so as to form an integral part thereof. Suitable means are provided for applying hydraulic pressure to the piston 24 at the end of piston rod 21 so as to

move the piston rod 21 and the shaft 19a and roller 19 to the left in Fig. 1 for applying tension to the band 17, all for a purpose that will appear presently. At its right end in Fig. 1, the band 17 passes over a power roller 25 rotating on a shaft 26 carried by fixed opposed brackets 27. Band 17 passes also over a shaping roller 28 mounted on a shaft 29 supported by bearings on the frame 10.

The shape of roller 28 can best be seen in Fig. 4, in which figure the relationship of the band 17 to roller 28 is also well illustrated. By applying considerable tension to the band 17 through operation of hydraulic ram cylinder 22, the band 17 will be shaped to conform to the roller 28 as has already been well indicated. Actually, the desired form of band 17 is yielded through contact of the band with the edges of the roller 28 rather than the body thereof, so that a pair of spaced surfaces could easily be substituted for the roller 28.

Between the shaping roller 28 and the power roller 25, the upper band 17 will pass over determining rolls 30 and 31. These rolls are each adapted for movement of adjustment in the axis of shafts 32, the shafts 32 being movable by the operation of suitable gear means 33 actuated by a shaft 34 when rotated by a hand wheel 35. Preferably, the two rolls 30, 31 will move together as is quite apparent from the drawings. As will further presently appear, the band 17 will also move relatively to other means for the cooling and guiding thereof.

The lower band 18 is controlled at its left end by a roller 36 functioning exactly as does the roller 19 and similarly controlled by a hydraulic ram 37. The band 18 also passes over a shaping roller 38 functioning exactly as does the roller 28. In addition, the lower band 18 passes over determining rolls 39 that need not be adjustable as are determining rolls 30, but which may be if desired. Band 18 also passes over a driving or power roll 40 rotating in a fixed axis 41 in substantially the same manner as power roll 25 rotates on the axis of shaft 26.

Referring now to Fig. 4, the lower band 18 is shown downwardly bowed because of its engagement with shaping roller 38, this roller 38 functioning as does the shaping roller 28 relatively to band 17. It will be noted that because of the bowed shape of the roller 38 and the band 18, it will be possible to create a bath for the molten metal designated by reference letter B in Fig. 1. Naturally, a considerable portion of the bath of metal will be in contact only with lower band 18, whereas at the right end of the bath of metal the upper portion thereof will be in contact with the upper band 17. Overlying the bath is the end 42 of a large spout S lined with a refractory material 43 for the flow of a rather considerable amount of metal into the bath of metal B. It will be noted especially from Fig. 1, that the metal flowing from the spout S will flow into the bath of metal B rather than onto the surface of the lower band 18. This is an exceedingly important feature of the invention because it is greatly preferred that the molten metal flow into the bath of metal rather than contact first one of the chilling bands, as I have earlier emphasized. Through the particular spacing of the bands to form the bath of metal in what I term the first zone of travel of the bands, it is possible to move into position the spout S, and to use a spout of that size that is

required for the efficient functioning of the invention.

The bands 17 and 18, moving as they do in the direction of the arrows D in Fig. 1, will carry with them metal from the bath B in the first zone and toward a second zone beyond the determining rolls 30. Naturally, that metal which is directly in contact with the bands will be chilled and solidified, and will move with the bands toward the determining rolls 30, 39 and between the said rolls into the second zone of travel of the bands. That metal which is somewhat spaced from the bands and interior of the metal solidified at the bands, will remain molten during this movement past the determining rolls whereby the determining rolls will determine the thickness of the metal strip to be formed in the mill by holding back an excess of molten metal. Naturally, the molten metal moving with the metal already solidified by the bands 17, 18 will be completely solidified within the second zone as will appear presently, to yield strip of that particular thickness desired.

Referring now to Fig. 5, it will be noted that the upper band 17 is maintained spaced from the upper surface member 44 of a cooling chamber 45. The particular cooling chamber is that one used for the upper band in the first zone of its travel, and overlies the band in the bath containing portion of the machine. Water is introduced into the chamber 45 and cools the band 17. Secured at each side edge of the surface member 44 is a yielding and stressed sealing member 46, pressing at 47 on the band 17 and preventing the flow of water from the chamber 45 outwardly of the machine. Should any water leak past the seals at 47, the band 17 is made wider than is the lower band 18 so that any surplus water will flow downwardly beyond the band 18 and will not tend to flow into the machine. The lower band 18 is similarly cooled through water flowing in a chamber 48 whose lower surface member is designated by reference numeral 49. Sealing members 50 function as do the members 46 just described.

As shown in Fig. 1, one end of the surface member 44 has secured thereto one end of a shroud or hood 54, the other end of this shroud being secured to a plate 56 forming the upper surface of a cooling chamber for the second zone. It is the purpose of shroud 54 to cover the roller 30 and to allow for the admission of cooling water about the roller 30. A similar shroud 55 is similarly positioned for determining roller 39.

The side dams for the metal are best illustrated in Figs. 2, 3 and 5, and preferably take the form of tubing 51. The edges of the upper band 17 may be pressed toward the upper surface of the square tubing 51 at each side of a part of the bath of metal by the sealing members 46, if necessary to contain the metal. Similarly, the edges of the lower band 18 may be applied to the lower surfaces of the tubing 51 where necessary to contain the metal. As shown at 52 in Fig. 3, water may be led into the tubes 51 so as to cool those tubes, the water leaving at 53. It will be noted also that the tubes approach one another more closely in the bath containing zone of the machine than at the extreme right hand end of the machine. This contributes draft to the metal and facilitates its movement. Thus, by continuously increasing the spacing of the side dams as the metal moves, less and less resistance to the movement of the metal strip is contributed by the side dams while those side dams nevertheless

perform their necessary function. It will be well to note in Fig. 3 that the lower band 18 seems to be narrower in the zone of the bath of metal than at its right hand end where it passes over power roll 40. Actually, the band is not narrower, but appears narrower because it is bowed to form the bath of metal which has already been described.

It is important here to note that the edges of the bands against tubing 51 are spaced substantially the same distance at all points where the bands function to solidify and form the metal strip. Thus, no thicker edge is formed opposite the bath of metal B, than is formed in the final finished strip. Therefore, there is no excess of solidified metal at the edges of the mill, and no problem created by the necessity for handling such excess, all as has been discussed generally earlier in this specification.

As the bands leave the first determining rolls 30, 39, they move into cooling relation to upper and lower cooling assemblies that are identical in operation. Referring now to Fig. 2, the upper cooling assembly comprises a plate 56 that may be of some suitable readily magnetized material and to one end of which is secured shroud 54. Preferably, plate 56 forms the soft core of an electromagnet similar to that used in magnetic chucks of the type found in grinding machines. Naturally, it is the function of the plate 56, when rendered magnetic by the proper flow of current, to pull the upper band 17 toward itself. To prevent this movement of the band 17 toward the plate 56, copper or brass spacers 58 are utilized, these spacers allowing the formation therefor of chambers between the band 17 and the plate 56. In these open chambers cooling water is introduced to chill the band 17. Even though this cooling water is introduced at considerable pressure, and sufficient normally to distort the band 17, it will not do so because of the influence of the magnetic plate 56 holding the band 17 firmly against the rigid spacers 58. In this way, it is possible to cool the band 17 while guiding it and holding it against distortion, and thereby maintaining accurate gauge of the product. In Fig. 2a I show a preferred form of spacer in the shape of a button 58a, making possible application of water against a greater area of cooling band 17.

The plate 56 carries at its sides sealing members 59 functioning as do the sealing members 46 already described, and particularly operating to maintain the band 17 against the tubing 51 earlier described and which functions as the side dams of the metal moving in the second zone of my machine. This metal is designated by reference letter M and is shown in Fig. 1 as leaving the second set of determining rolls 31, 39. As has already been indicated, the cooling and controlling of the lower band 18 in Fig. 2 is the same as the cooling and controlling of the band 17. It will be noted, however, that the upper band 17 is wider than the lower band 18 so that any water escaping from the upper cooling chambers will be deflected from movement against the metal that is being cooled and formed between the two bands. Both bands are wider than the rolls on which they are guided in order to allow for the shaping of the bands without stretching the edges thereof beyond the elastic limit.

For drying the upper band 17, I utilize a gas carrying pipe 60 containing a series of nozzles 61 and normally maintained by a spring 62 in the position of Fig. 1. Upon the starting of the operation of the power rolls 25, 40 incidental to

the operation of the machine, an electromagnet 63 is energized and serves through a lever 64 to rotate the pipe 60 against the force of the spring 62. At that time flames issuing from the series 5 of nozzles 61 will be directed against the upper band 17 and will maintain that band dry and warm. However, when the rotation of power rolls 25, 40 is stopped, the electromagnet 63 will be de-energized and a spring 62 will rotate the pipe 60 10 so as to direct the flame issuing through nozzles 61 away from the band 17. An exactly similar structure is utilized for lower band 18 and is well illustrated in Fig. 1.

It will be remembered that the roller 19, best 15 seen in Figs. 1, 3 and 6, rotates on the axis of a shaft 19a carried by spaced arms 20 that in turn are carried by the piston rod 21 of a hydraulic ram cylinder 22. I have found that by rotating the roller 19 bodily with its shaft 19a and arms 20 in the axis of piston 21, the band 17 is directed 25 in one direction or another transversely to its direction of travel. Thus, if in Fig. 6, as an example, the arms 20 are rotated in one direction in the axis of shaft 21, the band 17 will be moved in one lateral direction. On the other hand, bodily rotation of the roller 19 and its shaft 19a in the opposite direction will tend to move the band laterally in the opposed direction.

For determining accurately the lateral position 30 of the band 17, I utilize that mechanism shown diagrammatically in Fig. 6. Thus, in Fig. 6 there extends from one of the arms 20 a bracket 65 having a ball and socket connection 66 with a piston having rod portion 67 extending into a cylinder 68, there being a piston head 69 fixed to the said rod 67. A spring 70 tends to maintain the piston head downwardly in the cylinder 68 and therefore maintains the roller 19 in particular relation to the remainder of the machine. Hydraulic 35 fluid may be introduced into the cylinder 68 through means of a pipe 71 so as to move the piston head 69 and piston rod 67 against the pressure of spring 70, thereby rotating the roller 19 bodily in the axis of the piston rod 21. Fluid 40 under pressure is thus introduced into the cylinder 68 under the control of a valve 72 actuated by an electromagnet coil 73 under the control of a switch at 14. Thus, whenever the band 17 45 closes the switch at point 14, electricity will flow through the coil 73 lifting the valve rod 72. Fluid under pressure then flows from a fluid source through pipe 75 into the chamber 76, chamber 77, and pipe 71 into cylinder 68. Upon the breaking of the circuit at 14, the valve rod 72 will be 50 dropped and fluid under pressure will no longer flow into the cylinder 68. In this way, the roller 19 may be tilted in response to the lateral position of the band 17 as will now appear clearly to those skilled in the art. By this arrangement, I can maintain the bands in their proper positions regardless of certain inevitable variations in temperature that may cause the bands to move 55 toward one end or the other of the rolls.

In Fig. 7, I show a modification of my invention 60 in which no side dams, as such, are utilized. Thus, the edges of bands 17, 18 are brought together by the sealing members 46, 50, thereby containing the metal moving between the bands. This is an entirely satisfactory arrangement 65 where thin strip is to be formed.

In Fig. 8 I show a further modification in which 70 to prevent friction between the cooling band 17 and the upper sealing member 46, there are provided moving ribbons 79, positioned as illustrated. These ribbons move in such relation to the cool-

ing band 17 as to accept any wear through the pressure of the sealing members 46. Similar traveling ribbons 86 are used for protecting the lower cooling band 18.

In Fig. 9, I show another modification of my invention whereby I do away with the necessity of providing stationary cooling dams, thereby also eliminating the necessary wear that occurs between the side dams and the cooling bands 17 and 18. Thus, to form the side dams, I use a series of narrow ribbons 81 running over suitable rollers 82, 83, and 84. These ribbons travel between the bands 17 and 18 at the edges thereof and act to contain the metal so that it does not escape from between the bands 17, 18. Actually, molten metal will not run into such small crevices as may occur between these ribbons, and the ribbons are of such width that contact with the molten metal is not sufficiently great to require separate cooling means. Actually, where very thin metal is to be formed by the machine, a single endless ribbon may be provided, but where the metal is of greater thickness, it may be necessary to use a number of these metal ribbons 81.

In Fig. 11, I show diagrammatically a further modified form of side dam utilizing a sprocket chain 85 running over a pair of sprockets 86, the said sprockets 86 being driven in particular speed relation to the metal strip formed by the machine, and preferably so that there will be no relative motion between the chain and the metal in that zone where the chain moves parallel to the metal. Secured to chain links are copper blocks 87 that lie end to end as particularly shown at 88 in Fig. 11. In this way, through movement of the said copper blocks 87 between the upper and lower bands 17 and 18, side dams will be formed by the blocks in a very effective fashion.

In Fig. 12 I illustrate a section of an apparatus for casting continuous billets that here are of square cross section. The apparatus comprises four moving bands 91 cooled at their outer surfaces by the flow of water as shown at W. Cup-shaped sealing members 92 are provided for sealing the moving edges of the bands 91 and for holding within the shape formed by the bands the metal that is poured continuously into the chamber 93 formed by the bands, all as will appear quite clearly.

Those skilled in the art will now readily appreciate, especially with regard to the modification of my invention illustrated in Fig. 1, that I have provided a very inexpensive and effective mill capable of great production. Thus, I utilize very readily replaceable chilling surfaces that function to chill and form metal strip without any pressure whatsoever, thereby preventing the segregation of alloys in a most effective manner. Further, the power required by my invention is quite low because in the main, the bands merely serve to form a conveyor for the metal, the metal moving readily from the bath into the cooling and forming zone. Moreover, the end product may be delivered in any desired width and in varying gauges for further operations, all with considerable variety. In addition, I am able to form a bath of metal utilizing my chilling surfaces, while simultaneously maintaining the thickness of the metal at the edges of the bath of substantially the same thickness as the final metal strip turned out by my mill.

I believe that with the particular description of the invention already presented, and the general remarks found at the beginning of the speci-

fication, the complete utility of my invention and my contribution to this art will be appreciated.

I now claim:

1. In a process of continuously casting metal, the steps of introducing molten metal between longitudinally extending elements some at least of which travel longitudinally, cooling the said elements so as to freeze a peripherally continuous layer of the metal thereagainst, and thereafter progressively decreasing the thickness of the cross-sectional area of the metal between said longitudinally traveling elements while simultaneously progressively increasing the width of the cross-sectional area of the metal between said elements, and completing the shaping of the cast metal to the final desired cross-section prior to the complete freezing of the metal between said elements.
2. A process of casting metal which comprises bringing a pair of longitudinally traveling elements into longitudinally opposed moving relation to one another with one at least of said elements laterally distorted so that the edges of said elements are more closely approached to each other than central portions thereof, introducing molten metal into the space between said elements as so moving, cooling said elements whereby progressively to freeze said molten metal thereagainst, and during the continued longitudinal travel of both of said elements with the metal therebetween, progressively removing the distortion of the distorted element prior to the complete freezing of the metal so as to diminish the spacing of central portions of said elements while maintaining the relative spacing of the said edges.
3. A process of continuously casting wide, flat, thin shapes from molten metal which comprises casting the metal continuously between moving, laterally bowed, cooled bands in a shape which increases in thickness from its edges to its mid-section, and, prior to the complete solidification of the cast metal, progressively flattening said bands while confining the metal therebetween whereby to diminish the mid-section thickness of the metal to be cast and produce a substantially flat cast shape.
4. In a machine of the character described, a pair of endless belts mounted on sheaves so as to have adjacent flights, means for driving said belts in the same direction and at the same speed in said adjacent flights, means for imparting opposed transverse concave curvature to said belts in parts of said flights, means to bring said belts into edgewise juxtaposition while so curved, means to introduce molten metal between said belts when in said juxtaposition, means for cooling said belts, and means beyond the means to introduce molten metal in the direction of travel of said flights for flattening said belts transversely while maintaining said edgewise juxtaposition.
5. In a machine of the class described, a pair of moving metal bands, means for guiding said bands for linear longitudinal travel in the same direction in one zone of their travel with their edges in juxtaposed metal retaining relation and including means for bowing at least one of said bands outwardly transversely relatively to the other so that said bands form therebetween a chamber for a bath of metal, means for feeding molten metal into said chamber, means for progressively flattening said bowed band while guiding both said bands for longitudinal movement beyond said chamber with said metal there-

between to define between said bands the section of metal to be cast therebetween, and means for cooling said bands as they move longitudinally.

6. In a machine of the class described, a pair of moving metal bands, means for guiding said bands for linear longitudinal travel in the same direction including means for bowing at least one of said bands transversely outwardly away from the other band to form a chamber deeper at its transverse center than at its side edges and gradually decreasing in depth toward the edges thereof, means for feeding molten metal into said chamber to form a bath of metal, additional guide means longitudinally beyond said metal feeding means for progressively flattening said bowed band relatively to its edges while guiding both said bands for longitudinal movement beyond said chamber to define between them the flattened section of metal to be cast therebetween, and means for cooling said bands as they move longitudinally to progressively cool and freeze the metal therebetween.

7. In a machine of the class described, a pair of moving continuous metal bands, means for guiding said bands for linear longitudinal travel in the same direction in one flight of their travel including means for bowing at least one of said bands transversely outwardly relatively to the other so that said bands form therebetween a concave chamber for a bath of metal, means for feeding molten metal into said chamber, means for progressively flattening said bowed band relatively to the other band to flatten the cross-section of the metal between said bands while guiding both said bands for longitudinal movement beyond said chamber to define between the bands the flattened section of the metal shape to be cast therebetween, and means for cooling said bands.

8. In a machine of the class described, a pair of moving metal bands, longitudinally extending side dams between said bands for coaction with the edges thereof, means for guiding said bands for linear longitudinal travel in the same direction in one part of the path of their travel with each edge in contact with a side dam and including means for bowing at least one of said bands transversely outwardly relatively to the other so that said bands and side dams form therebetween a chamber for a bath of metal, means for feeding molten metal into said chamber, means for progressively flattening said bowed band while guiding both said bands for longitudinal movement with their edges in contact with said side dams beyond said chamber to define between said bands the section of metal to be cast therebetween, and means for cooling said bands as they move longitudinally to progressively cool the metal between said bands.

9. In the combination of claim 8 the feature that said side dams are a plurality of thin, narrow continuous moving metal belts.

10. In a machine of the class described, a pair of moving metal bands, longitudinally extending side dams between said bands for coaction with the edges thereof, means for guiding said bands for linear longitudinal travel in the same direction in one zone of their travel with each edge in contact with a side dam and including means for bowing at least one of said bands outwardly relatively to the other so that said bands and side dams form therebetween a chamber for a bath of metal, means for feeding molten metal into said chamber, means for progressively flattening said bowed band while guiding both said bands for longitudinal movement with their edges

in contact with said side dams beyond said chamber to define between said bands the flattened section of metal to be cast therebetween, said side dams diverging outwardly away from one another longitudinally in the direction of movement of said bands, and means for cooling said bands.

11. In the combination of claim 10 the feature that said side dams are a plurality of thin, narrow continuous moving metal belts.

12. In a machine of the class described, a pair of moving metal bands, means guiding said bands for linear longitudinal travel in the same direction in one zone of their travel and including means for holding the edges of said bands in contact with one another and for bowing at least one of said bands outwardly relatively to the other so that said bands form therebetween a chamber for a bath of metal, means for feeding molten metal into said chamber, additional guide means longitudinally beyond said first guide means for progressively flattening said bowed band while holding the edges of said bands in contact during continued longitudinal movement of said bands to define between said bands the flattened section of metal to be cast therebetween, and means for cooling said bands as they move longitudinally to progressively cool the metal between said bands.

13. In a machine of the class described, a pair of moving metal bands, longitudinally extending side dams between said bands for coaction with the edges thereof, means for guiding said bands for linear longitudinal travel in the same direction with the distance separating at least parts of said bands gradually decreasing to define therebetween first a cross-sectional area of relatively greater thickness and then progressively a cross-sectional area of substantially less thickness, means formed as part of said guide means for guiding the edges of said bands for longitudinal movement in contact with said side dams, means for feeding molten metal into the chamber formed between said bands and said side dams, said metal feeding means feeding said metal to said chamber where the cross-sectional area of the metal is of said relatively greater thickness, and said side dams diverging outwardly away from one another longitudinally in the direction of movement of said bands whereby said bands define therebetween progressively a cross-sectional area of metal the width of which progressively increases as the thickness of the cross-sectional area decreases.

CLARENCE W. HAZELETT.
